(57) **CLAIM**

The ornamental design for a display screen with set of color icons, as shown and described.

DESCRIPTION

The patent or application file contains at least one drawing executed in color. Copies of this patent or patent application with color drawings(s) will be provided by the Office upon request and payment of the necessary fee.

FIG. 1 is a front view of a display screen with set of color icons showing the new design;

FIG. 2 is a front view of an icon from the set of color icons, shown in isolation;

FIG. 3 is a front view of a second icon from the set of color icons, shown in isolation;

FIG. 4 is a front view of a fourth icon from the set of color icons, shown in isolation; and,

FIG. 5 is a front view of a fifth icon from the set of color icons, shown in isolation.

The claim is directed to the collective appearance of the set of icons shown in FIG. 1.

The broken line showing of the rectangular regions and of the display screen portions is for environmental purposes only and forms no part of the claimed design.
